US00D552925S

(12) **United States Design Patent** (10) **Patent No.:** **US D552,925 S**
(45) **Date of Patent:** **** Oct. 16, 2007**

(54) **PAN**

(75) Inventor: **Gerd Kloppsteck**, Arnsberg (DE)

(73) Assignee: **Heinrich Berndes GmbH & Co. KG**,
Arnsberg (DE)

(**) Term: **14 Years**

(21) Appl. No.: **29/219,647**

(22) Filed: **Dec. 21, 2004**

(30) **Foreign Application Priority Data**

Jun. 23, 2004 (EM) 194 477

(51) **LOC (8) Cl.** **07-02**

(52) **U.S. Cl.** **D7/361**

(58) **Field of Classification Search** D7/361,
D7/391-393, 323, 395-396; 16/110.1, 405-407,
16/430-431, 441; 219/620-621, 725, 732;
220/573.1, 2, 3, 573.4, 5, 574; 99/324, 331

See application file for complete search history.
